(57) **CLAIM**

The ornamental design for a cereal piece, as shown and described.

DESCRIPTION

FIG. 1 is a perspective view of a cereal piece.

FIG. 2 is an alternative perspective view thereof;

FIG. 3 is a top plan view thereof;

FIG. 4 is a bottom plan view thereof;

FIG. 5 is a front elevation view thereof;

FIG. 6 is a rear elevation thereof;

FIG. 7 is a left side elevation view thereof; and,

FIG. 8 is a right side elevation view thereof.

The broken lines in the drawings illustrate portions of the cereal piece that form no part of the claimed design.

1 Claim, 4 Drawing Sheets(56)
